UNITED STATES PATENT OFFICE.

JAMES M. BRYCE, OF BEVERLY, NEW JERSEY.

DESIGN FOR A PRINTED FABRIC.

SPECIFICATION forming part of Design No. 13,076, dated July 25, 1882.

Application filed May 18, 1882. Term of patent 3½ years.

To all whom it may concern:

Be it known that I, JAMES M. BRYCE, of Beverly, in the county of Burlington and State of New Jersey, have invented a new and original Design for Printed Fabrics; and I do hereby declare that the following specification, taken in connection with the accompanying illustration, forming a part of the same, is a full, clear, and exact description thereof.

My design relates particularly to printed fabrics known as "calicoes," although it is equally applicable to silks, woolens, and other fabrics, either printed or woven.

It consists in the representation of animals and collections of fruits and leaves, as will hereinafter appear.

Referring to the illustration, A represents a buffalo, and A' a horse with an Indian mounted thereon. Immediately beneath these animals are arranged collections of leaves and fruits

B, from which sprays of flowers C project; but said sprays may be omitted, if desired.

The fabric may be produced in any preferred variety or combination of colors for giving a desirable effect to the design.

What I claim, and desire to secure by Letters Patent, is—

1. The design for printed and other fabrics, consisting of animals and collections of fruits and leaves, substantially as described and shown.

2. The design for printed and other fabrics, consisting of animals, collections of fruits and leaves, and sprays of flowers, substantially as described and shown.

JAMES M. BRYCE.
